(57) **ABSTRACT**

Novel tools and techniques are provided for implementing data transmission, and, more particularly, to methods, systems, and apparatuses for implementing data transmission utilizing techniques used for transient state computing with optics. In various embodiments, a photo-transmitter system of a chromatic transient state data transmission system might send, over optical transmission media, a data signal comprising a series of chromabit values, by emitting, using a set of colored light emitters, a combination of colors representing each chromabit value. A photo-receiver system of the chromatic transient state data transmission system that is communicatively coupled to the photo-transmitter system via the optical transmission media might receive the data signal, each distinguishable color as detected by each photoreceptor corresponding to a combination of emitted colors. A computing system might autonomously convert the data signal comprising the series of chromabit values into a converted data signal that is compatible with a receiving device.

**CROSS-REFERENCES TO RELATED
APPLICATIONS**

This application is a continuation-in-part of U.S. patent application Ser. No. 16/132,108 (the “108 application”), filed on Sep. 14, 2018 by Ronald A. Lewis, entitled, “Method and System for Implementing Transient State Computing with Optics,” which is a continuation of U.S. patent application Ser. No. 15/853,337 (the “337 application”), filed on Dec. 22, 2017 by Ronald A. Lewis, entitled, “Method and System for Implementing Transient State Computing with Optics,” which claims priority to U.S. Patent Application Ser. No. 62/526,239 (the “239 application”), filed on Jun. 28, 2017 by Ronald A. Lewis, entitled, “Transient State Computing with Optics,” the entire teachings of which are incorporated herein by reference in their entirety for all purposes.

The respective disclosures of these applications/patents (which this document refers to collectively as the “Related Applications”) are incorporated herein by reference in their entirety for all purposes.

COPYRIGHT STATEMENT

A portion of the disclosure of this patent document contains material that is subject to copyright protection. The copyright owner has no objection to the facsimile reproduction by anyone of the patent document or the patent disclosure as it appears in the Patent and Trademark Office patent file or records, but otherwise reserves all copyright rights whatsoever.

FIELD

The present disclosure relates, in general, to methods, systems, and apparatuses for implementing computing, and, more particularly, to methods, systems, and apparatuses for implementing transient state computing with optics. The present disclosure further relates, in general, to methods, systems, and apparatuses for implementing data transmission, and, more particularly, to methods, systems, and apparatuses for implementing data transmission utilizing techniques used for transient state computing with optics.

BACKGROUND

Conventional computing devices (such as silicon-based computing devices or the like) utilize computing logic using two states (which are represented by binary values “0” and “1”). Such binary computing devices require a large array of arithmetic logic units (“ALUs”), each performing bitwise logic operations or the like, to compute large computational problems. Power and heat issues arise when such binary computing devices are scaled up in attempts to increase computational capabilities. In efforts to overcome the limitations of binary computing devices, several groups and entities have researched or developed quantum computing systems, which are based on qubits that reflect quantum states. Although quantum computing systems utilize more than two states, conventional quantum computing systems (which are potentially capable of using far less power than

2

binary computing devices) are costly to manufacture, costly to operate (e.g., some quantum computing systems require power to cool a qubit to 10 times colder than interstellar space in order to tip a qubit or to change states, etc.), currently difficult to scale-up, and have issues related to detection of state (i.e., in the process of detecting the state of a qubit, the very state of the qubit might change due to quantum mechanical effects).

In addition, conventional data transmission, such as fiber optic data transmission, are reliant on a single color laser for transmission of data. Accordingly, it is limited by the number of data bits that can be sent per fiber at a time.

Hence, there is a need for more robust and scalable solutions for implementing computing, and, more particularly, to methods, systems, and apparatuses for implementing transient state computing with optics. There is also a need for more robust and scalable solutions for implementing data transmission, and, more particularly, to methods, systems, and apparatuses for implementing data transmission utilizing techniques used for transient state computing with optics.

BRIEF DESCRIPTION OF THE DRAWINGS

A further understanding of the nature and advantages of particular embodiments may be realized by reference to the remaining portions of the specification and the drawings, in which like reference numerals are used to refer to similar components. In some instances, a sub-label is associated with a reference numeral to denote one of multiple similar components. When reference is made to a reference numeral without specification to an existing sub-label, it is intended to refer to all such multiple similar components.

FIG. 1 is a schematic diagram illustrating a system for implementing transient state computing with optics, in accordance with various embodiments.

FIGS. 2A and 2B are schematic diagrams illustrating various embodiments of photo-optic compute cells that may be used for implementing transient state computing with optics.

FIG. 3 is a schematic diagram illustrating an embodiment of a system for implementing transient state computing with optics.

FIG. 4 is a schematic diagram illustrating another embodiment of a system for implementing transient state computing with optics.

FIGS. 5A and 5B are schematic diagrams illustrating various embodiments of transient states that are possible with use of primary colors, in accordance with various embodiments.

FIG. 6 is a flow diagram illustrating a method for implementing transient state computing with optics, in accordance with various embodiments.

FIG. 7 is a schematic diagram illustrating an embodiment of a system for implementing data transmission utilizing techniques used for transient state computing with optics.

FIG. 8 is a schematic diagram illustrating another embodiment of a system for implementing data transmission utilizing techniques used for transient state computing with optics.

FIGS. 9A and 9B are flow diagrams illustrating a method for implementing data transmission utilizing techniques used for transient state computing with optics, in accordance with various embodiments.

DETAILED DESCRIPTION OF CERTAIN EMBODIMENTS

Overview

Various embodiments provide tools and techniques for implementing computing, and, more particularly, to methods, systems, and apparatuses for implementing transient state computing with optics.

In various embodiments, a chromatic transient state computing system might receive one or more input values and might assign a chromabit value to each of the one or more input values. The chromatic transient state computing system might include a plurality of sets of colored light emitting diodes ("LEDs") and a corresponding set of photoreceptors. Each distinguishable color as detected by one of the photoreceptors might correspond to a combination of colors emitted by a set of colored LEDs, each distinguishable color representing a chromabit value. The chromatic transient state computing system might perform a computing operation using the assigned chromabit values each corresponding to each of the one or more input values, and might output one or more output values resulting from the computing operation.

In some embodiments, each set of colored LEDs might comprise three differently colored LEDs. In some cases, the three differently colored LEDs might comprise a red LED, a yellow LED, and a blue LED. In some instances, each set of colored LEDs might represent 8 possible states, each possible state representing a possible chromabit value.

According to some embodiments, intensity of each colored LED might be controllable based on input current. The range of light intensity produced by changing input current to each colored LED might result in a series of distinguishable colors each representing a chromabit value. In some cases, each set of colored LEDs might represent 216 possible states, each possible state representing a possible chromabit value. Alternatively, each set of colored LEDs might represent 4,096 possible states, each possible state representing a possible chromabit value. In yet other alternative embodiments, each set of colored LEDs might represent 16,777,216 possible states, each possible state representing a possible chromabit value.

Merely by way of example, in some embodiments, each set of colored LEDs might comprise four or more of a red LED, an orange LED, a yellow LED, a green LED, a cyan LED, a blue LED, or a violet LED, and/or the like. According to some embodiments, the photoreceptors might each comprise one of a phototransistor or a set of photoresistors and an array of transistors, and/or the like.

The potential of such chromatic transient state computing systems as described herein (e.g., with respect to FIGS. 1-6) vastly overshadow the capabilities of conventional binary computing systems, as well as quantum computing systems (which although having more states than binary systems present issues including, but not limited to, cost in manufacturing, cost to operate (e.g., some quantum computing systems require power to cool a qubit to 10 times colder than interstellar space in order to tip a qubit or to change states, etc.), scalability, issues with detection that might affect states, etc.). In contrast to quantum computing systems, chromatic transient state computing systems can use existing parts (e.g., LEDs, photoreceptors, common electronic circuit components, etc.), thus allowing for low-cost, low-power, scalable high-level computing solutions. More importantly, the chromatic transient state computing system described herein (also referred to as a "photo-optic CPU"), requires significantly less power compared with both conventional

binary computing systems and currently available quantum computing systems, while providing the capability of using existing logic while also maintaining multiple Boolean states simultaneously. In some cases, individual LEDs might be used in the circuit to produce the chromatic transient state computing device. Alternatively, surface-mount device ("SMD") LEDs might be used instead, thereby further decreasing the size or footprint of each compute cell. Custom designs using SMD LEDs might also be utilized.

10 Various embodiments further provide tools and techniques for implementing data transmission, and, more particularly, to methods, systems, and apparatuses for implementing data transmission utilizing techniques used for transient state computing with optics.

15 In various embodiments, data transmission (such as fiber optic transmission or the like) might utilize the techniques described herein for implementing transient state computing with optics, thereby increasing the rate of data transmission as a greater number of data bits are transmitted over long distances (i.e., hundreds of meters or yards, tens or hundreds or thousands of kilometers or miles, etc.) via the one or more optical transmission media (e.g., fiber optic cables, or the like) using the different colored states.

20 In some embodiments, a photo-transmitter system of a chromatic transient state data transmission system might receive an initial data signal. In such cases, a computing system of the chromatic transient state data transmission system might determine whether the initial data signal is compatible with the chromatic transient state data transmission system (i.e., to determine whether the initial data signal comprises a series of chromabit values, or the like). If so, a receiver of the photo-transmitter system might directly relay the initial data signal to a set(s) of colored light emitters for transmission over one or more optical transmission media. If not, the computing system might autonomously convert the initial data signal to a data signal comprising a series of chromabit values (i.e., which might be compatible with the chromatic transient state data transmission system). The photo-transmitter system might send, over a first segment of the optical transmission media, the data signal (or compatible initial data signal) comprising the series of chromabit values, by emitting, using the set(s) of colored light emitters, a combination of colors representing each chromabit value.

25 The photo-receiver system(s) might receive the data signal (or the compatible initial data signal) via the first segment of the optical transmission media and via a set(s) of photoreceptors of a photo-receiver system of the chromatic transient state data transmission system, where each distinguishable color as detected by each photoreceptor of the set(s) of

30 photoreceptors of the photo-receiver system(s) corresponds to a combination of colors emitted by the set(s) of colored light emitters of the photo-transmitter system(s). In such cases, the computing system might determine whether the data signal is compatible with a receiver device(s) with

35 which the chromatic transient state data transmission system is connected (i.e., to determine whether the receiver device(s) is compatible with receiving data signals comprising a series of chromabit values, or the like). If so, the transmitter(s) of the photo-receiver system might directly relay the data signal to the receiver device(s). If not, the computing system might autonomously convert the data signal to a data signal that is compatible with the receiver data signals (i.e., by converting the data signal comprising the series of chromabit values into binary-based optical data signals, or the like).

40 These and other functions of the system for implementing transient state computing with optics and/or the system for

implementing data transmission utilizing techniques used for transient state computing with optics are described in greater detail below with respect to figures.

The following detailed description illustrates a few exemplary embodiments in further detail to enable one of skill in the art to practice such embodiments. The described examples are provided for illustrative purposes and are not intended to limit the scope of the invention.

In the following description, for the purposes of explanation, numerous specific details are set forth in order to provide a thorough understanding of the described embodiments. It will be apparent to one skilled in the art, however, that other embodiments of the present invention may be practiced without some of these specific details. In other instances, certain structures and devices are shown in block diagram form. Several embodiments are described herein, and while various features are ascribed to different embodiments, it should be appreciated that the features described with respect to one embodiment may be incorporated with other embodiments as well. By the same token, however, no single feature or features of any described embodiment should be considered essential to every embodiment of the invention, as other embodiments of the invention may omit such features.

Unless otherwise indicated, all numbers used herein to express quantities, dimensions, and so forth used should be understood as being modified in all instances by the term "about." In this application, the use of the singular includes the plural unless specifically stated otherwise, and use of the terms "and" and "or" means "and/or" unless otherwise indicated. Moreover, the use of the term "including," as well as other forms, such as "includes" and "included," should be considered non-exclusive. Also, terms such as "element" or "component" encompass both elements and components comprising one unit and elements and components that comprise more than one unit, unless specifically stated otherwise.

Various embodiments described herein, while embodying (in some cases) software products, computer-performed methods, and/or computer systems, represent tangible, concrete improvements to existing technological areas, including, without limitation, computing technology, and/or the like. In other aspects, certain embodiments, can improve the functioning of computing systems themselves (e.g., computing systems, etc.), for example, by receiving, with a chromatic transient state computing system, one or more input values; assigning, with the chromatic transient state computing system, a chromabit value to each of the one or more input values, wherein the chromatic transient state computing system comprises a plurality of sets of colored light emitting diodes ("LEDs") and a corresponding set of photoreceptors, wherein each distinguishable color as detected by one of the photoreceptors corresponds to a combination of colors emitted by a set of colored LEDs, each distinguishable color representing a chromabit value; performing, with the chromatic transient state computing system, a computing operation using the assigned chromabit values each corresponding to each of the one or more input values; and outputting, with the chromatic transient state computing system, one or more output values resulting from the computing operation; and/or the like. In particular, to the extent any abstract concepts are present in the various embodiments, those concepts can be implemented as described herein by devices, software, systems, and methods that involve specific novel functionality (e.g., steps or operations), such as, increasing the computational capacity of a computing system by utilizing the transient states of colored

LEDs, and/or the like, to name a few examples, that extend beyond mere conventional computer processing operations (which are limited to the two states of conventional binary computing systems). These functionalities can produce tangible results outside of the implementing computer system, including, merely by way of example, increasing the computational capacity of computing systems, and/or the like, at least some of which may be observed or measured by customers and/or service providers.

10 In an aspect, a method might comprise receiving, with a chromatic transient state computing system, one or more input values. The method might further comprise assigning, with the chromatic transient state computing system, a chromabit value to each of the one or more input values. The 15 chromatic transient state computing system might comprise a plurality of sets of colored light emitting diodes ("LEDs") and a corresponding set of photoreceptors. Each distinguishable color as detected by one of the photoreceptors corresponds to a combination of colors emitted by a set of colored 20 LEDs, each distinguishable color representing a chromabit value. The method might also comprise performing, with the chromatic transient state computing system, a computing operation using the assigned chromabit values each corresponding to each of the one or more input values. The 25 method might further comprise outputting, with the chromatic transient state computing system, one or more output values resulting from the computing operation.

30 In some embodiments, each set of colored LEDs might comprise three differently colored LEDs. In some cases, the three differently colored LEDs might comprise a red LED, a yellow LED, and a blue LED. In some instances, each set of colored LEDs might represent 8 possible states, each possible state representing a possible chromabit value.

35 According to some embodiments, intensity of each colored LED might be controllable based on input current. The range of light intensity produced by changing input current to each colored LED might result in a series of distinguishable colors each representing a chromabit value. In some cases, each set of colored LEDs might represent 216 possible states, each possible state representing a possible chromabit value. Alternatively, each set of colored LEDs might represent 4,096 possible states, each possible state representing a possible chromabit value. In yet other alternative embodiments, each set of colored LEDs might represent 16,777,216 possible states, each possible state representing a possible chromabit value.

40 Merely by way of example, in some embodiments, each set of colored LEDs might comprise four or more of a red LED, an orange LED, a yellow LED, a green LED, a cyan LED, a blue LED, or a violet LED, and/or the like. According to some embodiments, the photoreceptors might each comprise one of a phototransistor or a set of photoresistors and an array of transistors, and/or the like.

45 In another aspect, a chromatic transient state computing system might comprise a plurality of sets of colored light emitting diodes ("LEDs") and a corresponding set of photoreceptors. A set of computing instructions might cause the chromatic transient state computing system to: receive one or more input values; assign a chromabit value to each of the one or more input values, wherein each distinguishable color as detected by one of the photoreceptors corresponds to a combination of colors emitted by a set of colored LEDs, each distinguishable color representing a chromabit value; perform a computing operation using the assigned chromabit 50 values each corresponding to each of the one or more input values; and output one or more output values resulting from the computing operation.

In some embodiments, each set of colored LEDs might comprise three differently colored LEDs. In some cases, the three differently colored LEDs might comprise a red LED, a yellow LED, and a blue LED. In some instances, each set of colored LEDs might represent 8 possible states, each possible state representing a possible chromabit value.

According to some embodiments, intensity of each colored LED might be controllable based on input current. The range of light intensity produced by changing input current to each colored LED might result in a series of distinguishable colors each representing a chromabit value. In some cases, each set of colored LEDs might represent 216 possible states, each possible state representing a possible chromabit value. Alternatively, each set of colored LEDs might represent 4,096 possible states, each possible state representing a possible chromabit value. In yet other alternative embodiments, each set of colored LEDs might represent 16,777,216 possible states, each possible state representing a possible chromabit value.

Merely by way of example, in some embodiments, each set of colored LEDs might comprise four or more of a red LED, an orange LED, a yellow LED, a green LED, a cyan LED, a blue LED, or a violet LED, and/or the like. According to some embodiments, the photoreceptors might each comprise one of a phototransistor or a set of photoresistors and an array of transistors, and/or the like.

In an aspect, a method might comprise sending, with a photo-transmitter system of a chromatic transient state data transmission system and over a segment of an optical transmission medium, a data signal comprising a series of chromabit values, by emitting, using a set of colored light emitters of the photo-transmitter system of the chromatic transient state data transmission system, a combination of colors representing each chromabit value; and receiving, with a photo-receiver system of the chromatic transient state data transmission system that is communicatively coupled to the photo-transmitter system via the segment of the optical transmission medium, the data signal comprising the series of chromabit values, wherein each distinguishable color as detected by each photoreceptor of one or more photoreceptors of the photo-receiver system corresponds to a combination of colors emitted by the set of colored light emitters of the photo-transmitter system. The method might further comprise autonomously converting, with a computing system of the chromatic transient state data transmission system, the data signal comprising the series of chromabit values into a converted data signal that is compatible with a receiving device with which the chromatic transient state data transmission system is connected.

In some embodiments, the optical transmission medium might comprise at least one fiber optic cable. In some cases, the one or more photoreceptors might each comprise one of a phototransistor or a set of photoresistors and an array of transistors, or the like.

According to some embodiments, the set of colored light emitters might each comprise one of a set of colored laser emitters or a set of colored light emitting diodes (“LEDs”), wherein each set of colored laser emitters might comprise three or more differently colored laser emitters, and wherein each set of colored LEDs might comprise three or more differently colored LEDs. In some instances, each set of colored light emitters might comprise three or more of a red light emitter, an orange light emitter, a yellow light emitter, a green light emitter, a cyan light emitter, a blue light emitter, or a violet light emitter, and/or the like. In some cases, each

set of colored light emitters might represent 8 possible states, each possible state representing a possible chromabit value.

Merely by way of example, in some instances, intensity of each colored light emitter might be controllable based on input current, wherein a range of light intensity produced by changing input current to each colored light emitter results in a series of distinguishable colors each representing a chromabit value. In some cases, each set of colored light emitters might represent 216 possible states, each possible state representing a possible chromabit value. Alternatively, each set of colored light emitters might represent 4,096 possible states, each possible state representing a possible chromabit value. Alternatively, each set of colored light emitters might represent 16,777,216 possible states, each possible state representing a possible chromabit value.

In some embodiments, the method might further comprise sending, with a transmitting device and to the photo-transmitter system of the chromatic transient state data transmission system to which the transmitting device is connected, an initial data signal; receiving, with the photo-transmitter system, the initial data signal; and autonomously converting, with the computing system of the chromatic transient state data transmission system, the initial data signal to the data signal comprising the series of chromabit values.

According to some embodiments, autonomously converting the data signal comprising the series of chromabit values into the converted data signal that is compatible with the receiving device with which the chromatic transient state data transmission system is connected might comprise determining, with the computing system of the chromatic transient state data transmission system, whether the data signal comprising the series of chromabit values is compatible with the receiving device; and based on a determination that the data signal comprising the series of chromabit values is not compatible with the receiving device, autonomously converting, with the computing system of the chromatic transient state data transmission system, the data signal comprising the series of chromabit values into the converted data signal that is compatible with the receiving device with which the chromatic transient state data transmission system is connected.

In some embodiments, the receiving device might comprise a repeater transmission system, wherein autonomously converting the data signal comprising the series of chromabit values into the converted data signal that is compatible with the receiving device with which the chromatic transient state data transmission system is connected might comprise sending, with a photo-transmitter system of the repeater transmission system and over a second segment of the optical transmission medium, a relayed data signal comprising a series of chromabit values, the relayed data signal being the same as the data signal. According to some embodiments, the receiving device might perform one or more computing operations using the converted data signal.

In another aspect, a chromatic transient state data transmission system might comprise a photo-transmitter system, a photo-receiver system that is communicatively coupled to the photo-transmitter system via a segment of an optical transmission medium, and a computing system. The photo-transmitter system might comprise at least one set of colored light emitters, wherein a first set of computing instructions causes the photo-transmitter system to: send, over the segment of the optical transmission medium, a data signal comprising a series of chromabit values, by emitting, using the at least one set of colored light emitters, a combination of colors representing each chromabit value. The photo-

receiver system might comprise at least one set of photoreceptors, wherein a second set of computing instructions causes the photo-receiver system to: receive, using the at least one set of photoreceptors, the data signal comprising the series of chromabit values, wherein each distinguishable color as detected by each photoreceptor of the at least one set of photoreceptors corresponds to a combination of colors emitted by the at least one set of colored light emitters of the photo-transmitter system. The computing system might comprise at least one processor and a non-transitory computer readable medium communicatively coupled to the at least one processor. The non-transitory computer readable medium might have stored thereon computer software comprising a third set of computing instructions that, when executed by the at least one processor, causes the computing system to: determine whether the data signal comprising the series of chromabit values is compatible with a receiving device with which the chromatic transient state data transmission system is connected; based on a determination that the data signal comprising the series of chromabit values is compatible with the receiving device, autonomously relay the data signal comprising the series of chromabit values to the receiving device; and based on a determination that the data signal comprising the series of chromabit values is not compatible with the receiving device, autonomously convert the data signal comprising the series of chromabit values into a converted data signal that is compatible with the receiving device.

In some embodiments, the optical transmission medium might comprise at least one fiber optic cable. In some cases, the set of colored light emitters might each comprise one of a set of colored laser emitters or a set of colored light emitting diodes (“LEDs”), wherein each set of colored laser emitters might comprise three or more differently colored laser emitters, and wherein each set of colored LEDs might comprise three or more differently colored LEDs.

According to some embodiments, intensity of each colored light emitter might be controllable based on input current, wherein the range of light intensity produced by changing input current to each colored light emitter results in a series of distinguishable colors each representing a chromabit value.

In some instances, a transmitting device might be communicatively coupled to the photo-transmitter system, wherein the transmitting device might send an initial data signal to the photo-transmitter system, wherein a first set of computing instructions might cause the photo-transmitter system to receive the initial data signal, wherein the third set of computing instructions might cause the computing system to autonomously convert the initial data signal to the data signal comprising the series of chromabit values.

In some embodiments, the receiving device might comprise a repeater transmission system, wherein autonomously converting the data signal comprising the series of chromabit values into the converted data signal that is compatible with the receiving device with which the chromatic transient state data transmission system is connected might comprise sending, with a photo-transmitter system of the repeater transmission system and over a second segment of the optical transmission medium, a relayed data signal comprising a series of chromabit values, the relayed data signal being the same as the data signal.

Various modifications and additions can be made to the embodiments discussed without departing from the scope of the invention. For example, while the embodiments described above refer to particular features, the scope of this invention also includes embodiments having different com-

bination of features and embodiments that do not include all of the above described features.

Specific Exemplary Embodiments

We now turn to the embodiments as illustrated by the drawings. FIGS. 1-6 illustrate some of the features of the method, system, and apparatus for implementing computing, and, more particularly, to methods, systems, and apparatuses for implementing transient state computing with optics, as referred to above. FIGS. 7-9 illustrate some of the features of the method, system, and apparatus for implementing data transmission, and, more particularly, to methods, systems, and apparatuses for implementing data transmission utilizing techniques used for transient state computing with optics, as also referred to above. The methods, systems, and apparatuses illustrated by FIGS. 1-9 refer to examples of different embodiments that include various components and steps, which can be considered alternatives or which can be used in conjunction with one another in the various embodiments. The description of the illustrated methods, systems, and apparatuses shown in FIGS. 1-9 is provided for purposes of illustration and should not be considered to limit the scope of the different embodiments.

With reference to the figures, FIG. 1 is a schematic diagram illustrating a system 100 for implementing transient state computing with optics, in accordance with various embodiments.

In the non-limiting embodiment of FIG. 1, a chromatic transient state computing system 100 might comprise a plurality of compute cells 105, including, without limitation, a first compute cell 105a, a second compute cell 105b, through an Nth compute cell 105n. Each compute cell 105 might receive one or more input values, might assign a chromabit value to each of the one or more input values, might perform a computing operation using the assigned chromabit values each corresponding to each of the one or more input values, and might output one or more output values resulting from the computing operation.

We now turn to FIGS. 2A and 2B (collectively, “FIG. 2”), which are schematic diagrams illustrating various embodiments 200 and 200' of photo-optic compute cells that may be used for implementing transient state computing with optics.

In embodiment 200 of FIG. 2A, each photo-optic compute cell 105 might comprise a set of colored light emitting diodes (“LEDs”) 110a, 110b, through 110n (collectively, “LEDs 110” or the like) and a corresponding set of photoreceptors 115a, 115b, through 115n (collectively, “photoreceptors 115” or the like). Each distinguishable color as detected by one of the photoreceptors might correspond to a combination of colors emitted by a set of colored LEDs (the emitted light from each LED being depicted by triangular-shaped arrows 120 in FIG. 2), each distinguishable color representing a value referred to herein as a “chromabit value.” In some embodiments, each set of colored LEDs might comprise three differently colored LEDs. In some cases, the three differently colored LEDs might comprise a red LED, a yellow LED, and a blue LED, as depicted and described, e.g., in FIGS. 5A and 5B as primary colors.

According to some embodiments, each set of colored LEDs need not be the specific primary colors as shown in FIGS. 5A and 5B, but may comprise three or more (in some cases, four or more) of a red LED, an orange LED, a yellow LED, a green LED, a cyan LED, a blue LED, or a violet LED, and/or the like.

Referring to embodiment 200' of FIG. 2B, rather than a set of photoreceptors 115a, 115b, through 115n, a single pho-

photoreceptor 115 might be used to detect light emitted from all of the set of colored LEDs 110a, 110b, through 110n. In embodiments 200 and/or 200', each photoreceptor 115 might include, but is not limited to, one of a phototransistor (as depicted and described below with respect to FIG. 4, or the like) or a set of photoresistors and an array of transistors (as depicted and described below with respect to FIG. 3, or the like).

Each photo-optic compute cell 105 or 105' as described herein would replace a conventional arithmetic logic unit ("ALU") that performs bitwise logic operations, for instance. Because each photo-optic compute cell 105 or 105' uses at least three colored LEDs, at least base-8 logic operations can be achieved by each compute cell 105 or 105' compared with the base-2 or bitwise logic operations that conventional (e.g., silicon-based or binary) computing devices are capable of. That is, in a binary or bitwise logic system, there are 2 possible states (i.e., a "0" state or a "1" state), thus it is capable of performing base-2 operations. In contrast, a three colored LED-based photo-optic compute cell, as described herein and at its most basic level, comprises for each distinct colored LED (e.g., a primary color: red, yellow, and blue; or the like) two distinct states (i.e., an "on" state and an "off" state), which as illustrated in FIG. 5A results in 8 possible states (which might correspond to binary values or states "000," "100," "010," "001," "110," "011," "101," and "111"; or the like). In some cases, as described below, depending on the sensitivity of the photoreceptors used in each photo-optic compute cell, base-27 (e.g., for 3 colored LEDs each having 3 states (i.e., a "fully on" state, a "half on" state, and a "fully off" state), or the like), base-125 (e.g., for 3 colored LEDs each having 5 states (i.e., a "fully on" state, a "three-quarters on" state," a "half on" state, a "quarter on" state, and a "fully off" state), or the like), base-216 (e.g., for 3 colored LEDs each having 6 states (i.e., a "fully on" state, an "80% on" state," a "60% on" state, a "40% on" state, a "20% on" state, and a "fully off" state), or the like), base-4096 (e.g., for 3 colored LEDs each having 16 states, or the like), base-16777216 (e.g., for 3 colored LEDs each having 256 states, or the like), or more logic operations can be achieved by each compute cell. Other base values can also be used based on the three color configuration. For photo-optic compute cells having four or more colored LEDs, the base number of calculations can be further increased, thereby increasing the computational capabilities of the computing system.

Compared to the simplistic registers and control units of conventional base-2 or binary computing systems, however, more sophisticated registers and control units (and corresponding memory) would have to be implemented to operate the photo-optic compute cells and thus to operate the chromatic transient state computing systems. Regardless, the potential of such chromatic transient state computing systems vastly overshadow the capabilities of binary computing systems, and also quantum computing systems (which although having more states than binary systems present issues including, but not limited to, cost in manufacturing, cost to operate (e.g., some quantum computing systems require power to cool a qubit to 10 times colder than interstellar space in order to tip a qubit or to change states, etc.), scalability, issues with detection that might affect states, etc.). In contrast to quantum computing systems, chromatic transient state computing systems can use existing parts (e.g., LEDs, photoreceptors, common electronic circuit components, etc.), thus allowing for low-cost, low-power, scalable high-level computing solutions. More importantly, the chromatic transient state computing system described

herein (also referred to as a "photo-optic CPU"), requires significantly less power compared with both conventional binary computing systems and currently available quantum computing systems, while providing the capability of using existing logic while also maintaining multiple Boolean states simultaneously. In some cases, individual LEDs might be used in the circuit to produce the chromatic transient state computing device. Alternatively, surface-mount device ("SMD") LEDs might be used instead, thereby further decreasing the size or footprint of each compute cell. Custom designs using SMD LEDs might also be utilized. In some instances, each photo-optic compute cell might be encased in containers or semiconductor layers to block light and thus prevent cross-talk between or among adjacent compute cells.

The photo-optic compute cell 105 or 105' might correspond to each of the compute cells 105a-105n of chromatic transient state computing system 100 of FIG. 1, and the description of compute cells 105a-105n are applicable to the corresponding compute cell 105 or 105' of embodiment 200 or 200', respectively.

FIG. 3 is a schematic diagram illustrating an embodiment of a system 300 for implementing transient state computing with optics.

In the non-limiting embodiment of system 300 of FIG. 3, photo-optic compute cell(s) 305 might comprise one or more sets of colored LEDs 310 (in the example of FIG. 3, two sets of colored LEDs 310 and 310' are depicted, although the various embodiments are not so limited and any number of sets of colored LEDs 310 may be used per compute cell 305). Each set of colored LEDs might comprise three or more differently colored LEDs (three are shown in the example of FIG. 3). In some embodiments, each set of colored LEDs might include, without limitation, three or more (in some cases, four or more) of a red LED, an orange LED, a yellow LED, a green LED, a cyan LED, a blue LED, or a violet LED, and/or the like. Light emitted from each colored LED from the first set of LEDs 310 (denoted, " O_1 "; also denoted reference numeral 320) might be received by a photoreceptor 315, which might comprise a first photoresistor 325 (also denoted, " R_1 ") and an array of transistor gates 330 (also denoted, " T_1 "). The array of transistor gates 330 might communicatively couple to photoresistor 325. Likewise, light emitted from each colored LED from the second set of LEDs 310' (denoted, " O_2 "; also denoted reference numeral 320') might be received by a photoreceptor 315', which might comprise a second photoresistor 325' (also denoted, " R_2 ") and an array of transistor gates 330' (also denoted, " T_2 "). The array of transistor gates 330' might communicatively couple to photoresistor 325'. In some embodiments, system 300 might further comprise frequency clock(s) 335, which might be used to synchronize emission and reception/detection of light from each of the set of LEDs 310 or 310' (or from each LED of the set of LEDs 310 or 310').

The photo-optic compute cell(s) 305 might correspond to each of the compute cells 105a-105n of chromatic transient state computing system 100 of FIG. 1, and the description of compute cells 105a-105n are applicable to the corresponding photo-optic compute cell(s) 305 of system 300 of FIG. 3, respectively. The photo-optic compute cell(s) 305 might also correspond to the photo-optic compute cell 105 or 105' of embodiment 200 or 200', and the description of the photo-optic compute cell 105 or 105' of embodiment 200 or 200' are applicable to the corresponding photo-optic compute cell(s) 305 of system 300 of FIG. 3, respectively.

FIG. 4 is a schematic diagram illustrating another embodiment of a system 400 for implementing transient state computing with optics.

In the non-limiting embodiment of system 400 of FIG. 4, photo-optic compute cell(s) 405 might comprise one or more sets of colored LEDs 410 (in the example of FIG. 4, two sets of colored LEDs 410 and 410' are depicted, although the various embodiments are not so limited and any number of sets of colored LEDs 410 may be used per compute cell 405). Each set of colored LEDs might comprise three or more differently colored LEDs (three are shown in the example of FIG. 4). In some embodiments, each set of colored LEDs might include, without limitation, three or more (in some cases, four or more) of a red LED, an orange LED, a yellow LED, a green LED, a cyan LED, a blue LED, or a violet LED, and/or the like. Light emitted from each colored LED from the first set of LEDs 410 (denoted, "O₁"; also denoted reference numeral 420) might be received by a photoreceptor 415, which might comprise a first phototransistor 440 (also denoted, "PT₁"). The first phototransistor 440 might receive the colored light 420 from the first set of LEDs 410, and might output one or more output values. Likewise, light emitted from each colored LED from the second set of LEDs 410' (denoted, "O₂"; also denoted reference numeral 420') might be received by a photoreceptor 415', which might comprise a second phototransistor 440' (also denoted, "PT₂"). The second phototransistor 440' might receive the colored light 420' from the second set of LEDs 410', and might output one or more output values. In some embodiments, system 400 might further comprise frequency clock(s) 435, which might be used to synchronize emission and reception/detection of light from each of the set of LEDs 410 or 410' (or from each LED of the set of LEDs 410 or 410').

The photo-optic compute cell 405 might correspond to each of the compute cells 105a-105n of chromatic transient state computing system 100 of FIG. 1, and the description of compute cells 105a-105n are applicable to the corresponding compute cell 405 of system 400 of FIG. 4, respectively. The photo-optic compute cell(s) 405 might also correspond to the photo-optic compute cell 105 or 105' of embodiment 200 or 200', and the description of the photo-optic compute cell 105 or 105' of embodiment 200 or 200' are applicable to the corresponding photo-optic compute cell(s) 405 of system 400 of FIG. 4, respectively.

FIGS. 5A and 5B (collectively, "FIG. 5") are schematic diagrams illustrating various embodiments 500 and 500' of transient states that are possible with use of primary colors. Although three primary colors are depicted in FIG. 5, the various embodiments are not so limited, and any number and type of colors can be used for implementing transient state computing with optics, so long as the photoreceptors can distinguish among states corresponding to one or more combinations of these colors. With reference to FIG. 5, a three-colored set of light emitting diodes ("LEDs"), which in this case might include primary colors: red, yellow, and blue. According to some embodiments, however, each set of colored LEDs might comprise three or more (in some cases, four or more) of a red LED, an orange LED, a yellow LED, a green LED, a cyan LED, a blue LED, or a violet LED, and/or the like.

In embodiment 500 of FIG. 5A, for example, each colored LED might have two states: on and off. When all three primary LEDs are set to off (which might correspond to a bit state or bit value of "0"), no colors are emitted. When the red LED is set to the on state (which might correspond to a bit state or bit value of "1"), while the yellow and blue LEDs

are each set to the off state (which might correspond to a bit state or bit value of "0"), the color emitted may be red. When the yellow LED is set to the on state (which might correspond to a bit state or bit value of "1"), while the red and blue LEDs are each set to the off state (which might correspond to a bit state or bit value of "0"), the color emitted may be yellow. When the blue LED is set to the on state (which might correspond to a bit state or bit value of "1"), while the yellow and red LEDs are each set to the off state (which might correspond to a bit state or bit value of "0"), the color emitted may be blue. When the red and yellow LEDs are each set to the on state (which might correspond to a bit state or bit value of "1"), while the blue LED is set to the off state (which might correspond to a bit state or bit value of "0"), the color emitted may be orange. When the yellow and blue LEDs are each set to the on state (which might correspond to a bit state or bit value of "1"), while the red LED is set to the off state (which might correspond to a bit state or bit value of "0"), the color emitted may be green. When the red and blue LEDs are each set to the on state (which might correspond to a bit state or bit value of "1"), while the yellow LED is set to the off state (which might correspond to a bit state or bit value of "0"), the color emitted may be purple or magenta. When all three primary LEDs are set to on (which might correspond to a bit state or bit value of "1"), the color emitted may be white.

In some embodiments, each colored LED might have a range of states. In embodiment 500' of FIG. 5B, for instance, each colored LED might have a range between 0 and 255, resulting in 256 possible states, in some cases, each possible state representing a possible chromabit value. When all three primary LEDs are set to the fully off state (which might correspond to a bit state or bit value of "0"), no colors are emitted. When the red LED is set to the fully on state (which might correspond to a bit state or bit value of "255"), while the yellow and blue LEDs are each set to the fully off state (which might correspond to a bit state or bit value of "0"), the color emitted may be red. When the yellow LED is set to the fully on state (which might correspond to a bit state or bit value of "255"), while the red and blue LEDs are each set to the fully off state (which might correspond to a bit state or bit value of "0"), the color emitted may be yellow. When the blue LED is set to the fully on state (which might correspond to a bit state or bit value of "255"), while the yellow and red LEDs are each set to the fully off state (which might correspond to a bit state or bit value of "0"), the color emitted may be blue. When the red and yellow LEDs are each set to the fully on state (which might correspond to a bit state or bit value of "255"), while the blue LED is set to the fully off state (which might correspond to a bit state or bit value of "0"), the color emitted may be orange. When the yellow and blue LEDs are each set to the fully on state (which might correspond to a bit state or bit value of "255"), while the red LED is set to the fully off state (which might correspond to a bit state or bit value of "0"), the color emitted may be green. When the red and blue LEDs are each set to the fully on state (which might correspond to a bit state or bit value of "255"), while the yellow LED is set to the fully off state (which might correspond to a bit state or bit value of "0"), the color emitted may be purple or magenta. When all three primary LEDs are set to the fully on state (which might correspond to a bit state or bit value of "255"), the color emitted may be white.

Although not shown, the transient states between 0 and 255 for each primary color, resulting in 254 transient states per primary color. As such, the embodiment 500', having three primary colors each having 256 states, would have a

15

total of 16,777,216 possible states, each possible state representing a possible chromabit value. In the example of FIG. 5B', for instance, the triangular pointers beside the graduated range for each primary color might point to one of the 256 states. For example, in FIG. 5B, the pointer beside the graduated range for the red color might correspond to a bit state or bit value of "55," while the pointer beside the graduated range for the yellow color might correspond to a bit state or bit value of "127," and the pointer beside the graduated range for the blue color might correspond to a bit state or bit value of "200."

In alternative embodiments, although not shown in FIG. 5B, each of the primary colors might have 3 possible states (i.e., a "fully on" state, a "half on" state, and a "fully off" state, or the like), resulting in a total of 27 possible states, each possible state representing a possible chromabit value. Alternatively, each of the primary colors might have 5 possible states (i.e., a "fully on" state, a "three-quarters on" state, a "half on" state, a "quarter on" state, and a "fully off" state, or the like), resulting in a total of 125 possible states, each possible state representing a possible chromabit value. In an alternative embodiment, each of the primary colors might have 6 possible states (i.e., a "fully on" state, an "80% on" state, a "60% on" state, a "40% on" state, a "20% on" state, and a "fully off" state, or the like), resulting in a total of 216 possible states, each possible state representing a possible chromabit value. In another alternative embodiment, each of the primary colors might have 16 possible states, resulting in a total of 4,096 possible states, each possible state representing a possible chromabit value. Alternatively, each of the primary colors might have 4,096 possible states, resulting in a total of 68,719,476,736 possible states, each possible state representing a possible chromabit value. In yet another alternative embodiment, each of the primary colors might have 16,777,216 possible states, resulting in a total of 4,722,366,482,869,645,213,696 possible states, each possible state representing a possible chromabit value. The sensitivity of the photoreceptor(s)—which might each include, but is not limited to, one of a phototransistor or a set of photoresistors and an array of transistors, and/or the like—might provide the capability to sense or detect the possible chromabit values, and the number of total possible states may be limited to such capabilities. With higher possible states of each LED or of each set of LEDs, more sophisticated registers and control units (and corresponding memory) would have to be implemented to operate the photo-optic compute cells and thus to operate the chromatic transient state computing systems, as discussed above.

FIG. 6 is a flow diagram illustrating a method 600 for implementing transient state computing with optics, in accordance with various embodiments.

While the techniques and procedures are depicted and/or described in a certain order for purposes of illustration, it should be appreciated that certain procedures may be reordered and/or omitted within the scope of various embodiments. Moreover, while the method 600 illustrated by FIG. 6 can be implemented by or with (and, in some cases, are described below with respect to) the systems or embodiments 100, 200, 200', 300, 400, 500, and 500' of FIGS. 1, 2A, 2B, 3, 4, 5A, and 5B, respectively (or components thereof), such methods may also be implemented using any suitable hardware (or software) implementation. Similarly, while each of the systems or embodiments 100, 200, 200', 300, 400, 500, and 500' of FIGS. 1, 2A, 2B, 3, 4, 5A, and 5B, respectively (or components thereof), can operate according to the method 600 illustrated by FIG. 6 (e.g., by

16

executing instructions embodied on a computer readable medium), the systems or embodiments 100, 200, 200', 300, 400, 500, and 500' of FIGS. 1, 2A, 2B, 3, 4, 5A, and 5B, respectively (or components thereof) can each also operate according to other modes of operation and/or perform other suitable procedures.

In the non-limiting embodiment of FIG. 6, method 600, at block 605, might comprise receiving, with a chromatic transient state computing system, one or more input values. At block 610, method 600 might comprise assigning, with the chromatic transient state computing system, a chromabit value to each of the one or more input values. The chromatic transient state computing system might include, without limitation, a plurality of sets of colored light emitting diodes ("LEDs") and a corresponding set of photoreceptors. Each distinguishable color as detected by one of the photoreceptors might correspond to a combination of colors emitted by a set of colored LEDs, each distinguishable color representing a chromabit value. In some embodiments, the photoreceptors might each comprise one of a phototransistor or a set of photoresistors and an array of transistors, and/or the like.

Method 600 might further comprise performing, with the chromatic transient state computing system, a computing operation using the assigned chromabit values each corresponding to each of the one or more input values (block 615) and outputting, with the chromatic transient state computing system, one or more output values resulting from the computing operation (block 620).

In some embodiments, each set of colored LEDs might comprise three differently colored LEDs. In some cases, the three differently colored LEDs comprise a red LED, a yellow LED, and a blue LED. In some instances, each set of colored LEDs might represent 8 possible states, each possible state representing a possible chromabit value (e.g., as illustrated and described above with respect to FIG. 5A, or the like).

According to some embodiments, intensity of each colored LED is controllable based on input current, wherein the range of light intensity produced by changing input current to each colored LED results in a series of distinguishable colors each representing a chromabit value (e.g., as illustrated and described above with respect to FIG. 5B, or the like). In some instances, each set of colored LEDs might represent 216 possible states, each possible state representing a possible chromabit value.

In some embodiments, the light intensity for each colored LED might range between 0 and 15 (representing a fully on state, a fully off state, and 14 transient states between). In other words, each set of colored LEDs (having three colored LEDs) might represent 4,096 possible states, each possible state representing a possible chromabit value (not shown). Alternatively, the light intensity for each colored LED might range between 0 and 255 (representing a fully on state, a fully off state, and 254 transient states between). In other words, each set of colored LEDs (having three colored LEDs) might represent 16,777,216 possible states, each possible state representing a possible chromabit value (e.g., as illustrated and described above with respect to FIG. 5B, or the like). In some cases, the light intensity for each colored LED might allow for a greater range, allowing for a greater number of possible states, each possible state representing a possible chromabit value (not shown).

In some aspects, each set of colored LEDs might include, without limitation, four or more of a red LED, an orange LED, a yellow LED, a green LED, a cyan LED, a blue LED, or a violet LED, and/or the like.

FIG. 7 is a schematic diagram illustrating an embodiment of a system 700 for implementing data transmission utilizing techniques used for transient state computing with optics.

In the non-limiting embodiment of FIG. 7, system 700 might comprise a chromatic transient state data transmission system 705, which might comprise a photo-transmitter system(s) 710, a photo-receiver system(s) 715, and one or more computing systems 720. In some embodiments, the photo-transmitter system(s) 710 might each include, without limitation, a receiver(s) 725, a set(s) of colored light emitters 730, and/or the like. Similarly, the photo-receiver system(s) 715 might each include, but is not limited to, a set(s) of photoreceptors 740, a transmitter(s) 745, and/or the like. The photo-transmitter system(s) 710 might communicatively couple with the photo-receiver system(s) 715 via one or more optical transmission media 735a or 735b (collectively, “optical transmission media 735” or the like; including, but not limited to, one or more fiber optic cables, or the like). In particular, the set(s) of colored light emitters 730 of each photo-transmitter system 710 might communicatively couple with the set(s) of photoreceptors 740 of each corresponding photo-receiver system 715 via the one or more optical transmission media 735 (including, but not limited to, one or more fiber optic cables, or the like). In some cases, the one or more computing systems 720 might include, without limitation, a first computing system 720a, a second computing system 720b, a third computing system 720c, and so on. In some instances, at least one of the photo-transmitter system(s) 710 might comprise the first computing system 720a, while at least one of the photo-receiver system(s) 715 might comprise the second computing system 720b, and the third computing system 720c might be comprised by the chromatic transient state data transmission system 705 and might be communicatively coupled (either via wireless or wired connections; wireless being depicted by lightning bolt symbols in FIG. 7) to the photo-transmitter system(s) 710 and the photo-receiver system(s) 715, yet external to any of the photo-transmitter system(s) 710 and the photo-receiver system(s) 715. According to some embodiments, the chromatic transient state data transmission system 705 might further comprise at least one frequency clock 750 that might be used to synchronize emission and reception/detection of light from each of the set(s) of colored light emitters 730. The at least one frequency clock 750, like the third computing system 720c, might be communicatively coupled (either via wireless or wired connections; wireless being depicted by lightning bolt symbols in FIG. 7) to the photo-transmitter system(s) 710 and the photo-receiver system(s) 715, yet external to any of the photo-transmitter system(s) 710 and the photo-receiver system(s) 715.

In operation, the photo-transmitter system(s) 710 might receive an initial data signal. In some cases, where a transmitter device (e.g., transmitter device(s) 755, or the like) is communicatively coupled to the photo-transmitter system(s) 710, the transmitter device might send the initial data signal to the receiver(s) 725 of the photo-transmitter system 710, which might receive the initial data signal from the transmitter device. In such cases, the first computing system 720a and/or the third computing system 720c might determine whether the initial data signal is compatible with the chromatic transient state data transmission system (i.e., to determine whether the initial data signal comprises a series of chromabit values, or the like). If so, the receiver(s) 725 might directly relay the initial data signal to the set(s) of colored light emitters 730 for transmission over the one or more optical transmission media 735. If not, the first computing system 720a and/or the third computing system 720c

might autonomously convert the initial data signal to a data signal comprising a series of chromabit values (i.e., which might be compatible with the chromatic transient state data transmission system).

5 The photo-transmitter system(s) 730 might send, over a first segment of the optical transmission media 735, the data signal (or compatible initial data signal) comprising the series of chromabit values, by emitting, using the set(s) of colored light emitters 730, a combination of colors representing each chromabit value. The photo-receiver system(s) 715 might receive the data signal (or the compatible initial data signal) via the first segment of the optical transmission media 735 and via the set(s) of photoreceptors 740, where each distinguishable color as detected by each photoreceptor of the set(s) of photoreceptors 740 of the photo-receiver system(s) 715 corresponds to a combination of colors emitted by the set(s) of colored light emitters 730 of the photo-transmitter system(s) 710. In such cases, the second computing system 720b and/or the third computing system 20 720c might determine whether the data signal is compatible with a receiver device(s) 760 with which the chromatic transient state data transmission system 705 is connected (i.e., to determine whether the receiver device(s) 760 is compatible with receiving data signals comprising a series 25 of chromabit values, or the like). If so, the transmitter(s) 745 might directly relay the data signal to the receiver device(s) 760. If not, the second computing system 720b and/or the third computing system 720c might autonomously convert the data signal to a data signal that is compatible with the receiver data signals (i.e., by converting the data signal comprising the series of chromabit values into binary-based optical data signals, or the like).

In some embodiments, in response to the receiver device(s) 760 receiving the relayed data signal or the converted data signal, the receiver device(s) 760 might perform one or more computing operations using one of the series of chromabit values of the data signal (as described above with respect to FIGS. 1-6, or the like) or data values of the converted data signal. Alternatively, the receiver device(s) 35 40 760 might comprise a repeater transmission system 760', which might comprise a receiver(s) 765 and a set(s) of colored light emitters 770, and/or the like, and thus compatible with the chromabit-based chromatic transient state data transmission system 705. In such cases, the receiver(s) 45 50 765 might receive the relayed data signal, and might send, via the set(s) of colored lights emitters 770, the received relayed data signal over a second segment 775 of the optical transmission media (and to a photo-receiver system(s) similar to photo-receiver system(s) 715, or the like), where the relayed data signal might be the same as the data signal and thus might comprise a series of chromabit values.

According to some embodiments, the set(s) of photoreceptors 740 might each include, but is not limited to, one of a phototransistor (not unlike the phototransistors 440 and 440' of FIG. 4, or the like) or a set of photoresistors and an array of transistors (not unlike the set of photoresistors 325 or 325' and the array of transistor gates 330 and 330' of FIG. 3, or the like), and/or the like. According to some embodiments, the set(s) of colored light emitters 730 and/or 770 might each include, without limitation, one of a set of colored laser emitters or a set of colored light emitting diodes (“LEDs”), or the like, where each set of colored laser emitters 730 and/or 770 might include, but is not limited to, three or more (in some cases, four or more) differently colored laser emitters, and where each set of colored LEDs might include, without limitation, three or more (in some cases, four or more) differently colored LEDs, or the like. In

some instances, each set of colored light emitters 730 and/or 770 might comprise three or more (in some cases, four or more) of a red light emitter, an orange light emitter, a yellow light emitter, a green light emitter, a cyan light emitter, a blue light emitter, or a violet light emitter, and/or the like. Merely by way of example, in some cases, each set of colored light emitters 730 and/or 770 might represent 8 possible states, each possible state representing a possible chromabit value.

According to some embodiments, intensity of each colored light emitter 730 and/or 770 might be controllable based on input current, where a range of light intensity produced by changing input current to each colored light emitter 730 and/or 770 might result in a series of distinguishable colors each representing a chromabit value. In some instances, each set of colored light emitters 730 and/or 770 might represent 216 possible states, each possible state representing a possible chromabit value. Alternatively, each set of colored light emitters 730 and/or 770 might represent 4,096 possible states, each possible state representing a possible chromabit value. In yet another alternative, each set of colored light emitters 730 and/or 770 might represent 16,777,216 possible states, each possible state representing a possible chromabit value.

In the manner as described herein, by utilizing the techniques described herein for implementing transient state computing with optics (such as described above with respect to FIGS. 1-6), the rate of data transmission may be increased as a greater number of data bits are transmitted over long distances (i.e., hundreds of meters or yards, tens or hundreds or thousands of kilometers or miles, etc.) via the one or more optical transmission media (e.g., fiber optic cables, or the like) using the different colored states.

At least some of these and other functions of the system 700 (and its components) are described in greater detail below with respect to FIGS. 8 and 9.

FIG. 8 is a schematic diagram illustrating another embodiment of a system 800 for implementing data transmission utilizing techniques used for transient state computing with optics.

In the non-limiting embodiment of FIG. 8, system 800 might comprise a chromatic transient state data transmission system 805, which might comprise a photo-transmitter system(s) 810, a photo-receiver system(s) 815, and one or more computing systems 820. In some embodiments, the photo-transmitter system(s) 810 might each include, without limitation, a receiver(s) 825, a set(s) of colored light emitters 830, and/or the like. Similarly, the photo-receiver system(s) 815 might each include, but is not limited to, a set(s) of photoreceptors 840, a transmitter(s) 845, and/or the like. The photo-transmitter system(s) 810 might communicatively couple with the photo-receiver system(s) 815 via one or more optical transmission media 835 (including, but not limited to, one or more fiber optic cables, or the like). In particular, the set(s) of colored light emitters 830 of each photo-transmitter system 810 might communicatively couple with the set(s) of photoreceptors 840 of each corresponding photo-receiver system 815 via the one or more optical transmission media 835 (including, but not limited to, one or more fiber optic cables, or the like). In some cases, the one or more computing systems 820 might include, without limitation, a first computing system 820a, a second computing system 820b, a third computing system 820c, and so on. In some instances, at least one of the photo-transmitter system(s) 810 might comprise the first computing system 820a, while at least one of the photo-receiver system(s) 815 might comprise the second computing system 820b, and the third computing system 820c might be comprised by the

chromatic transient state data transmission system 805 and might be communicatively coupled (either via wireless or wired connections; wireless being depicted by lightning bolt symbols in FIG. 8) to the photo-transmitter system(s) 810 and the photo-receiver system(s) 815, yet external to any of the photo-transmitter system(s) 810 and the photo-receiver system(s) 815. According to some embodiments, the chromatic transient state data transmission system 805 might further comprise at least one frequency clock 850 that might be used to synchronize emission and reception/detection of light from each of the set(s) of colored light emitters 830. The at least one frequency clock 850, like the third computing system 820c, might be communicatively coupled (either via wireless or wired connections; wireless being depicted by lightning bolt symbols in FIG. 8) to the photo-transmitter system(s) 810 and the photo-receiver system(s) 815, yet external to any of the photo-transmitter system(s) 810 and the photo-receiver system(s) 815.

In operation, the photo-transmitter system(s) 810 might receive an initial data signal. In such cases, the first computing system 820a and/or the third computing system 820c might determine whether the initial data signal is compatible with the chromatic transient state data transmission system (i.e., to determine whether the initial data signal comprises a series of chromabit values, or the like). If so, the receiver(s) 825 might directly relay the initial data signal to the set(s) of colored light emitters 830 for transmission over the one or more optical transmission media 835. If not, the first computing system 820a and/or the third computing system 820c might autonomously convert the initial data signal to a data signal comprising a series of chromabit values (i.e., which might be compatible with the chromatic transient state data transmission system).

The photo-transmitter system(s) 830 might send, over a first segment of the optical transmission media 835, the data signal (or compatible initial data signal) comprising the series of chromabit values, by emitting, using the set(s) of colored light emitters 830, a combination of colors representing each chromabit value. The photo-receiver system(s) 815 might receive the data signal (or the compatible initial data signal) via the first segment of the optical transmission media 835 and via the set(s) of photoreceptors 840, where each distinguishable color as detected by each photoreceptor of the set(s) of photoreceptors 840 of the photo-receiver system(s) 815 corresponds to a combination of colors emitted by the set(s) of colored light emitters 830 of the photo-transmitter system(s) 810. In such cases, the second computing system 820b and/or the third computing system 820c might determine whether the data signal is compatible with a receiver device(s) with which the chromatic transient state data transmission system 805 is connected (i.e., to determine whether the receiver device(s) is compatible with receiving data signals comprising a series of chromabit values, or the like). If so, the transmitter(s) 845 might directly relay the data signal to the receiver device(s). If not, the second computing system 820b and/or the third computing system 820c might autonomously convert the data signal to a data signal that is compatible with the receiver data signals (i.e., by converting the data signal comprising the series of chromabit values into binary-based optical data signals, or the like).

As illustrated in FIG. 8, similar to the photo-optic compute cells of FIG. 2, the set(s) of light emitters 830 might comprise emitters 830a-830n that each emit colored light (as depicted by triangular-shaped arrows 880 in FIG. 8), while the set(s) of photoreceptors 840 might comprise photoreceptors 840a-840n that might receive the emitted colored

light (as depicted by triangular-shaped arrows 880' in FIG. 8) over the one or more optical transmission media 835 (e.g., one or more fiber optic cables, or the like), or the like. Each distinguishable color as detected by at least one of the photoreceptors might correspond to a combination of colors emitted by a set of colored LEDs (the emitted light from each LED being depicted by triangular-shaped arrows 880 or 880' in FIG. 8), each distinguishable color representing a value referred to herein as a "chromabit value." According to some embodiments, the set(s) of colored light emitters 830 might each include, without limitation, one of a set of colored laser emitters or a set of colored light emitting diodes ("LEDs"), or the like, where each set of colored laser emitters 830 might include, but is not limited to, three or more (in some cases, four or more) differently colored laser emitters, and where each set of colored LEDs might include, without limitation, three or more (in some cases, four or more) differently colored LEDs, or the like. In some instances, each set of colored light emitters 830 might comprise three or more (in some cases, four or more) of a red light emitter, an orange light emitter, a yellow light emitter, a green light emitter, a cyan light emitter, a blue light emitter, or a violet light emitter, and/or the like. Merely by way of example, in some cases, each set of colored light emitters 830 might represent 8 possible states, each possible state representing a possible chromabit value.

According to some embodiments, intensity of each colored light emitter 830 might be controllable based on input current, where a range of light intensity produced by changing input current to each colored light emitter 830 might result in a series of distinguishable colors each representing a chromabit value. In some instances, each set of colored light emitters 830 might represent 216 possible states, each possible state representing a possible chromabit value. Alternatively, each set of colored light emitters 830 might represent 4,096 possible states, each possible state representing a possible chromabit value. In yet another alternative, each set of colored light emitters 830 might represent 16,777,216 possible states, each possible state representing a possible chromabit value.

According to some embodiments, the set(s) of photoreceptors 840 might each include, but is not limited to, one of a phototransistor (not unlike the phototransistors 440 and 440' of FIG. 4, or the like) or a set of photoresistors and an array of transistors (not unlike the set of photoresistors 325 or 325' and the array of transistor gates 330 and 330' of FIG. 3, or the like), and/or the like.

The chromatic transient state data transmission system 805, the photo-transmitter system(s) 810, the photo-receiver system(s) 815, the one or more computing systems 820a-820c, the receiver(s) 825, the set(s) of colored light emitters 830, the one or more optical transmission media 835, the set(s) of photoreceptors 840, the transmitter(s) 845, and the at least one frequency clock 850 of system 800 of FIG. 8 are otherwise similar, if not identical, to the chromatic transient state data transmission system 705, the photo-transmitter system(s) 710, the photo-receiver system(s) 715, the one or more computing systems 720a-820c, the receiver(s) 725, the set(s) of colored light emitters 730, the one or more optical transmission media 735, the set(s) of photoreceptors 740, the transmitter(s) 745, and the at least one frequency clock 750, respectively, of system 700 of FIG. 7, and the descriptions of these components of system 700 are applicable to the corresponding components of system 800, respectively.

FIGS. 9A and 9B (collectively, "FIG. 9") are flow diagrams illustrating a method 900 for implementing data transmission utilizing techniques used for transient state

computing with optics, in accordance with various embodiments. Method 900 of FIG. 9A continues onto FIG. 9B following the circular marker denoted, "A."

While the techniques and procedures are depicted and/or described in a certain order for purposes of illustration, it should be appreciated that certain procedures may be reordered and/or omitted within the scope of various embodiments. Moreover, while the method 900 illustrated by FIG. 9 can be implemented by or with (and, in some cases, are described below with respect to) the systems or embodiments 100, 200, 200', 300, 400, 500, 500', 700, and 800 of FIGS. 1, 2A, 2B, 3, 4, 5A, 5B, 7, and 8, respectively (or components thereof), such methods may also be implemented using any suitable hardware (or software) implementation. Similarly, while each of the systems or embodiments 100, 200, 200', 300, 400, 500, 500', 700, and 800 of FIGS. 1, 2A, 2B, 3, 4, 5A, 5B, 7, and 8, respectively (or components thereof), can operate according to the method 900 illustrated by FIG. 9 (e.g., by executing instructions embodied on a computer readable medium), the systems or embodiments 100, 200, 200', 300, 400, 500, 500', 700, and 800 of FIGS. 1, 2A, 2B, 3, 4, 5A, 5B, 7, and 8, respectively (or components thereof) can each also operate according to other modes of operation and/or perform other suitable procedures.

In the non-limiting embodiment of FIG. 9, method 900, at optional block 905, might comprise sending, with a transmitting device and to a photo-transmitter system of a chromatic transient state data transmission system to which the transmitting device is connected, an initial data signal. At optional block 910, method 900 might comprise receiving, with the photo-transmitter system, the initial data signal. Method 900 might further comprise determining, with a computing system of the chromatic transient state data transmission system, whether the initial data signal is compatible with the chromatic transient state data transmission system (optional block 915). If not, method 900 might proceed to the process at optional block 920. If so, the method 900 might proceed to the process at block 925. At optional block 920, method 900 might comprise autonomously converting, with the computing system of the chromatic transient state data transmission system, the initial data signal to a data signal comprising a series of chromabit values. Method 900 might continue to the process at block 925.

At block 925, method 900 might comprise sending, with the photo-transmitter system of the chromatic transient state data transmission system and over a segment of an optical transmission medium, the data signal comprising the series of chromabit values, by emitting, using a set of colored light emitters of the photo-transmitter system of the chromatic transient state data transmission system, a combination of colors representing each chromabit value. Method 900, at block 930, might comprise receiving, with a photo-receiver system of the chromatic transient state data transmission system that is communicatively coupled to the photo-transmitter system via the segment of the optical transmission medium, the data signal comprising the series of chromabit values, wherein each distinguishable color as detected by each photoreceptor of one or more photoreceptors of the photo-receiver system corresponds to a combination of colors emitted by the set of colored light emitters of the photo-transmitter system. Method 900 might continue onto the process at block 935 in FIG. 9B following the circular marker denoted, "A."

At block 935 in FIG. 9B (following the circular marker denoted, "A"), method 900 might comprise determining,

with the computing system of the chromatic transient state data transmission system, whether the data signal comprising the series of chromabit values is compatible with a receiving device with which the chromatic transient state data transmission system is connected. If not, method 900 might proceed to the process at block 940. If so, the method 900 might proceed to the process at block 945. At block 940, method 900 might comprise autonomously converting, with the computing system of the chromatic transient state data transmission system, the data signal comprising the series of chromabit values into a converted data signal that is compatible with the receiving device with which the chromatic transient state data transmission system is connected.

Method 900 might continue to the process at block 945.

At block 945, method 900 might comprise receiving, with the receiver device, the data signal or the converted data signal. In some embodiments, method 900 might further comprise performing, with the receiver device, one or more computing operations using one of the series of chromabit values of the data signal or data values of the converted data signal (block 950). Alternatively, the receiver might comprise a repeater transmission system, and method 900 might comprise sending, with a photo-transmitter system of the receiver device (serving as the repeater transmission system) and over a second segment of the optical transmission medium, a relayed data signal comprising a series of chromabit values, the relayed data signal being the same as the data signal.

In some embodiments, the optical transmission medium might include, without limitation, at least one fiber optic cable, or the like. In some cases, the one or more photoreceptors might each include, but is not limited to, one of a phototransistor or a set of photoresistors and an array of transistors, and/or the like. According to some embodiments, the set of colored light emitters might each include, without limitation, one of a set of colored laser emitters or a set of colored light emitting diodes ("LEDs"), or the like, where each set of colored laser emitters might include, but is not limited to, three or more differently colored laser emitters, and where each set of colored LEDs might include, without limitation, three or more differently colored LEDs, or the like. In some instances, each set of colored light emitters might comprise three or more (in some cases, four or more) of a red light emitter, an orange light emitter, a yellow light emitter, a green light emitter, a cyan light emitter, a blue light emitter, or a violet light emitter, and/or the like. Merely by way of example, in some cases, each set of colored light emitters might represent 8 possible states, each possible state representing a possible chromabit value.

According to some embodiments, intensity of each colored light emitter might be controllable based on input current, where a range of light intensity produced by changing input current to each colored light emitter might result in a series of distinguishable colors each representing a chromabit value. In some instances, each set of colored light emitters might represent 216 possible states, each possible state representing a possible chromabit value. Alternatively, each set of colored light emitters might represent 4,096 possible states, each possible state representing a possible chromabit value. In yet another alternative, each set of colored light emitters might represent 16,777,216 possible states, each possible state representing a possible chromabit value.

While certain features and aspects have been described with respect to exemplary embodiments, one skilled in the art will recognize that numerous modifications are possible. For example, the methods and processes described herein

may be implemented using hardware components, software components, and/or any combination thereof. Further, while various methods and processes described herein may be described with respect to particular structural and/or functional components for ease of description, methods provided by various embodiments are not limited to any particular structural and/or functional architecture but instead can be implemented on any suitable hardware, firmware and/or software configuration. Similarly, while certain functionality is ascribed to certain system components, unless the context dictates otherwise, this functionality can be distributed among various other system components in accordance with the several embodiments.

Moreover, while the procedures of the methods and processes described herein are described in a particular order for ease of description, unless the context dictates otherwise, various procedures may be reordered, added, and/or omitted in accordance with various embodiments. Moreover, the procedures described with respect to one method or process may be incorporated within other described methods or processes; likewise, system components described according to a particular structural architecture and/or with respect to one system may be organized in alternative structural architectures and/or incorporated within other described systems. Hence, while various embodiments are described with—or without—certain features for ease of description and to illustrate exemplary aspects of those embodiments, the various components and/or features described herein with respect to a particular embodiment can be substituted, added and/or subtracted from among other described embodiments, unless the context dictates otherwise. Consequently, although several exemplary embodiments are described above, it will be appreciated that the invention is intended to cover all modifications and equivalents within the scope of the following claims.

What is claimed is:

1. A method, comprising:
sending, with a photo-transmitter system of a chromatic transient state data transmission system and over a segment of an optical transmission medium, a data signal comprising a series of chromabit values, by emitting, using a set of colored light emitters of the photo-transmitter system of the chromatic transient state data transmission system, a combination of colors representing each chromabit value;
receiving, with a photo-receiver system of the chromatic transient state data transmission system that is communicatively coupled to the photo-transmitter system via the segment of the optical transmission medium, the data signal comprising the series of chromabit values, wherein each distinguishable color as detected by each photoreceptor of one or more photoreceptors of the photo-receiver system corresponds to a combination of colors emitted by the set of colored light emitters of the photo-transmitter system; and
autonomously converting, with a computing system of the chromatic transient state data transmission system, the data signal comprising the series of chromabit values into a converted data signal that is compatible with a receiving device with which the chromatic transient state data transmission system is connected.

2. The method of claim 1, wherein the optical transmission medium comprises at least one fiber optic cable.

3. The method of claim 1, wherein the one or more photoreceptors each comprises one of a phototransistor or a set of photoresistors and an array of transistors.

4. The method of claim 1, wherein the set of colored light emitters each comprises one of a set of colored laser emitters or a set of colored light emitting diodes (“LEDs”), wherein each set of colored laser emitters comprises three or more differently colored laser emitters, and wherein each set of colored LEDs comprises three or more differently colored LEDs. 5

5. The method of claim 4, wherein each set of colored light emitters comprises three or more of a red light emitter, an orange light emitter, a yellow light emitter, a green light emitter, a cyan light emitter, a blue light emitter, or a violet light emitter. 10

6. The method of claim 1, wherein each set of colored light emitters represents 8 possible states, each possible state representing a possible chromabit value. 15

7. The method of claim 1, wherein intensity of each colored light emitter is controllable based on input current, wherein a range of light intensity produced by changing input current to each colored light emitter results in a series of distinguishable colors each representing a chromabit value. 20

8. The method of claim 7, wherein each set of colored light emitters represents 216 possible states, each possible state representing a possible chromabit value. 25

9. The method of claim 7, wherein each set of colored light emitters represents 4,096 possible states, each possible state representing a possible chromabit value. 30

10. The method of claim 7, wherein each set of colored light emitters represents 16,777,216 possible states, each possible state representing a possible chromabit value. 35

11. The method of claim 1, further comprising:
sending, with a transmitting device and to the photo-transmitter system of the chromatic transient state data transmission system to which the transmitting device is connected, an initial data signal; 35
receiving, with the photo-transmitter system, the initial data signal; and
autonomously converting, with the computing system of the chromatic transient state data transmission system, the initial data signal to the data signal comprising the series of chromabit values. 40

12. The method of claim 1, wherein autonomously converting the data signal comprising the series of chromabit values into the converted data signal that is compatible with the receiving device with which the chromatic transient state data transmission system is connected comprises: 45

determining, with the computing system of the chromatic transient state data transmission system, whether the data signal comprising the series of chromabit values is compatible with the receiving device; and 50
based on a determination that the data signal comprising the series of chromabit values is not compatible with the receiving device, autonomously converting, with the computing system of the chromatic transient state data transmission system, the data signal comprising the series of chromabit values into the converted data signal that is compatible with the receiving device with which the chromatic transient state data transmission system is connected. 55

13. The method of claim 1, wherein the receiving device comprises a repeater transmission system, wherein autonomously converting the data signal comprising the series of chromabit values into the converted data signal that is compatible with the receiving device with which the chromatic transient state data transmission system is connected comprises: 60

sending, with a photo-transmitter system of the repeater transmission system and over a second segment of the optical transmission medium, a relayed data signal comprising a series of chromabit values, the relayed data signal being the same as the data signal. 65

14. The method of claim 1, wherein the receiving device performs one or more computing operations using the converted data signal. 70

15. A chromatic transient state data transmission system, comprising:

a photo-transmitter system, comprising:
at least one set of colored light emitters;
wherein a first set of computing instructions causes the photo-transmitter system to:
send, over a segment of an optical transmission medium, a data signal comprising a series of chromabit values, by emitting, using the at least one set of colored light emitters, a combination of colors representing each chromabit value; 20

a photo-receiver system that is communicatively coupled to the photo-transmitter system via the segment of the optical transmission medium, the photo-receiver system comprising:

at least one set of photoreceptors;
wherein a second set of computing instructions causes the photo-receiver system to:
receive, using the at least one set of photoreceptors, the data signal comprising the series of chromabit values, wherein each distinguishable color as detected by each photoreceptor of the at least one set of photoreceptors corresponds to a combination of colors emitted by the at least one set of colored light emitters of the photo-transmitter system; 25

a computing system, comprising:

at least one processor; and
a non-transitory computer readable medium communicatively coupled to the at least one processor, the non-transitory computer readable medium having stored thereon computer software comprising a third set of computing instructions that, when executed by the at least one processor, causes the computing system to:

determine whether the data signal comprising the series of chromabit values is compatible with a receiving device with which the chromatic transient state data transmission system is connected; based on a determination that the data signal comprising the series of chromabit values is compatible with the receiving device, autonomously relay the data signal comprising the series of chromabit values to the receiving device; and 40

based on a determination that the data signal comprising the series of chromabit values is not compatible with the receiving device, autonomously convert the data signal comprising the series of chromabit values into a converted data signal that is compatible with the receiving device. 45

16. The chromatic transient state data transmission system of claim 15, wherein the optical transmission medium comprises at least one fiber optic cable. 50

17. The chromatic transient state data transmission system of claim 15, wherein the set of colored light emitters each comprises one of a set of colored laser emitters or a set of colored light emitting diodes (“LEDs”), wherein each set of colored laser emitters comprises three or more differently colored laser emitters. 55

27

28

colored laser emitters, and wherein each set of colored LEDs comprises three or more differently colored LEDs.

18. The chromatic transient state data transmission system of claim **15**, wherein intensity of each colored light emitter is controllable based on input current, wherein the range of light intensity produced by changing input current to each colored light emitter results in a series of distinguishable colors each representing a chromabit value. 5

19. The chromatic transient state data transmission system of claim **15**, wherein a transmitting device is communicatively coupled to the photo-transmitter system, wherein the transmitting device sends an initial data signal to the photo-transmitter system, wherein a first set of computing instructions causes the photo-transmitter system to receive the initial data signal, wherein the third set of computing 15 instructions causes the computing system to autonomously convert the initial data signal to the data signal comprising the series of chromabit values.

20. The chromatic transient state data transmission system of claim **15**, wherein the receiving device comprises a 20 repeater transmission system, wherein autonomously converting the data signal comprising the series of chromabit values into the converted data signal that is compatible with the receiving device with which the chromatic transient state data transmission system is connected comprises: 25

sending, with a photo-transmitter system of the repeater transmission system and over a second segment of the optical transmission medium, a relayed data signal comprising a series of chromabit values, the relayed data signal being the same as the data signal. 30
